CLAIM

The ornamental design for a toy gun as shown and described.

DESCRIPTION

FIG. 1 is a left, rear and top perspective view of a toy gun showing my new design;

FIG. 2 is a right, front and bottom perspective view thereof;

FIG. 3 is a left view thereof;

FIG. 4 is a right view thereof;

FIG. 5 is a front elevational view thereof;

FIG. 6 is a rear elevational view thereof;

FIG. 7 is a top plan view thereof;

FIG. 8 is a bottom plan view thereof; and,

FIG. 9 is an enlarged view of area “9” in FIG. 1.

The long dash-short dash broken lines shown in FIGS. 1 and 9 are for the purpose of indicating the enlarged partial views and form no part of the claimed design. The evenly broken lines illustrate portions of the article that form no part of the claimed design.

1 Claim, 9 Drawing Sheets
